UNITED STATES PATENT OFFICE.

WILLIAM O. DEWSBURY, OF THOMPSONVILLE, CONNECTICUT, ASSIGNOR TO THE HART-FORD CARPET CORPORATION, OF THOMPSONVILLE, CONNECTICUT, A CORPORATION OF CONNECTICUT.

DESIGN FOR CARPET OR RUG.

43,758.

Specification for Design.

Patented Apr. 1, 1913.

Application filed February 28, 1913. Serial No. 751,369. Term of patent 3½ years.

To all whom it may concern:

Be it known that I, WILLIAM O. DEWSBURY, a citizen of the United States, residing in Thompsonville, in the county of Hartford and State of Connecticut, have invented a new, original, and ornamental Design for a Carpet or Rug, of which the following is a specification, reference being had to the accompanying drawing, forming part thereof.

The figure is a face view of approximately a quarter section of a carpet or rug showing my design.

I claim:

The ornamental design for a carpet or rug as shown.

WM. O. DEWSBURY.

Witnesses:

H. B. BRAINARD,
G. E. RYAN.
